DESCRIPTION

The FIGURE is a front view of a display screen or portion thereof with graphical user interface showing the claimed design.

The outermost dashed broken lines in the FIGURE show a display screen or portion thereof, and form no part of the claimed design. The other dashed broken lines in the FIG-URE show portions of the graphical user interface that form no part of the claimed design.

The dot-dash broken lines and the area within the dot-dash lines show portions of the graphical user interface that form no part of the claimed design.
